(57) **CLAIM**

The ornamental design for a cheerleading stunt training device, as shown and described.

DESCRIPTION

FIG. 1 is a top front perspective view of a cheerleading stunt training device showing our new design;

FIG. 2 is a bottom front perspective view thereof;

FIG. 3 is a top plan view thereof;

FIG. 4 is a bottom plan view thereof;

FIG. 5 is a front elevation view thereof;

FIG. 6 is a rear elevation view thereof; and,

FIG. 7 is a right side elevation view thereof, with the left side elevation view being a mirror image thereof.

The broken lines shown in the drawings depict portions of the cheerleading stunt training device that form no part of the claimed design.
